AUTOMATIC CUTOFF SWITCH WITH
BIMETALLIC STRIP CONTROL

Heinrich Schachtner, Schwetzingen, Baden, Germany, assignor to Stotz-Kontakt, Gesellschaft mit beschränkter Haftung, Mannheim-Neckarau, Germany, a corporation of Germany

Application September 14, 1937, Serial No. 163,711
In Germany September 21, 1936

3 Claims. (Cl. 200—113)

My invention relates to automatic cut-out switches, such as are employed for protecting electric circuits from overload by responding at a given current magnitude. In particular, my invention relates to this type of cut-out switch in which a bimetallic strip is employed which actuates the cut-out mechanism when the strip is heated by the excess current.

Bimetallic strip arrangements for actuating automatic switches for rapid opening and closing are already known. For instance in one prior art construction, the bi-metallic strip is fixed at one of its ends and carries pivotally attached to its free end a switch lever which pulls the circuit contacts open. Between this lever and the bimetallic strip is interposed a tilting spring in such manner that the strip and the switch lever form a toggle joint normally held by the spring in a stable position. In another similar prior art type, the bimetallic strip fixed at one end forms a toggle joint with a lever connected endwise with the other strip end and in which a spring tends to axially shift the lever into one or the other extreme position. In this case the movable contact is connected by way of a spring to the metal strip. Both of these prior art forms are actuated by the bending or deformation of the bimetallic strip, through heating by the excess current load up to the point where the spring power thus produced in the strip overcomes that of the tilting spring, so that the toggle joint is tripped and snaps from one extreme position over into the other extreme position.

The disadvantage of these prior art arrangements is that difficulty is encountered to provide the automatic switch with a so-called trip-free mechanism, that is, a mechanism which prevents tampering with the snap movement as well as forcibly holding the contacts in circuit-closing position during the occurrence or continuance of an excess load. Such a trip-free mechanism also is unnecessary with the above-mentioned known thermostatic control devices, since they are employed in heating appliances for automatic opening of the circuit on exceeding a given temperature of the heating appliance, and for the subsequent automatic reclosing of the circuit when the temperature has again dropped below the given value. Control of the contacts from outside, as by hand, therefore, does not occur in these prior devices.

In contrast to the above-described control switches for regulating the temperature of heating appliances, the present invention deals with automatic circuit breakers for the overload protection of electric house, factory and vehicle in-

stallations, or motors, and the like, and consists in providing these breakers with a bimetallic strip and a coating, spring-biased tilting lever in such a way that the strip forms part of a trip-free snap action mechanism. Especially according to the invention, a locking cam is arranged which is movable in the direction of an axis disposed substantially at right angles to the strip axis and tends to move, for instance by a spring, into the operating path of the bimetallic strip after the latter has responded to an overload, but is prevented by the strip from doing so in the closed contact position of the switch. As soon as the strip has moved into contact opening position, this cam is thrown in front of the bimetallic strip and prevents the latter, after it has cooled off, from returning the toggle joint into contact closing position, until the cam is withdrawn from outside, such as by hand. The great advantage of this arrangement resides in the fact that a trip-free mechanism with snap action is attained by an especially simple structure of great reliability, as will become apparent from the following description of an embodiment of my invention in connection with the accompanying light construction that it requires so little power for its operation, that it does not perceptibly interfere with the automatic opening operation of the contact mechanism, and that it is easily operated from outside to unlock the open contacts and to restore the device entirely to its automatic tendency to close, provided the strip has sufficiently cooled.

My invention is illustrated in the accompanying drawing in which—

Fig. 1 shows the switch in side elevation, partly in section and with the protecting casing removed.

Fig. 2 shows a plan view of Fig. 1 with the contacts in closed position, and

Fig. 3 a similar plan view with the contacts locked in open position.

Referring to these figures, on the switch base plate *a*, which may consist of any insulating material appropriate for the purpose, are mounted spaced apart the binding posts *b* and *c*. On post *b* is fixed a contact spring *d* which carries one of the switch contacts *e* at its outer end, and which is shaped so that it tends to throw this contact beyond the center line between the binding posts as shown in Fig. 3. On post *c* is fixed one end of a bimetallic strip *f* which carries the other switch contact *g* near its free end. A suitable distance beyond the free end of strip *f* is mounted on the base *a* a fixed pivot stud *h*, which supports pivotally attached to it a toggle lever *i*.

provided with a longitudinally movable extension element *i*'. A spring *j* between extension *i*' and lever *i* tends to move these elements apart. Extension *i*' is provided with a V-shaped recess at its outer end in which the free end of bimetallic strip *f* rests, thereby holding spring *j* under tension. In this manner this strip and lever *i* form a toggle joint which when in one extreme position closes contacts *e* and *g* (Fig. 2), and when in the other extreme position holds these contacts apart (Fig. 3). The normal spring tendency of strip *f* when cold moves the toggle joint into the contact closing position shown in Fig. 2, if the joint should be in open position.

On base *a* adjacent to strip *f* and between its contact *g* and binding post *c* is mounted a push pin *k*. This pin extends at right angles to the longitudinal axis of strip *f* and is longitudinally guided at its lower end in base *a* and near its upper end in a plate *o*, which forms part of the base structure. The upper end of pin *k* carries a hand push knob *m*, and between this knob and guide plate *o* a compression spring *n* is disposed on the pin, tending to throw the latter upwardly in Fig. 1, and toward the observer in Figs. 2 and 3. On pin *k* is mounted a cam element *p* which is normally, i. e. when the switch is closed, disposed in a recess of base *a* (see Fig. 1) and, due to the tension of spring *n*, rests lightly against the edge of bimetallic strip *f* (Fig. 2), which latter thus prevents it from leaving its recess. If the toggle joint is in the other extreme position with the contacts opened, as shown in Fig. 3, strip *f* is removed from cam *p* and the latter is thrust by spring *n* into the path of strip *f*, so that the latter comes to rest upon the periphery of the cam. The operation of this device is as follows. If, with the toggle joint in contact closing position as in Fig. 2, an overload occurs in the circuit, the current which passes through strip *f* heats the latter so that it bends and carries the toggle joint over its dead point from the position Fig. 2 into the position Fig. 3, whereby the contacts are quickly opened only after the joint passes the dead point, due to the tendency of spring *d* to follow contact *g* partway with its contact *e* and until the joint snaps into the open contact position. Cam *p* now moves in front of strip *f* as described, so that even when the latter cools, it is prevented from returning the toggle joint into contact closing position. Only by depressing push button *m* is cam *p* removed from the path of strip *f* and the latter, following its normal spring tension, snaps the toggle joint back into the contact closing position. This particular arrangement of the arresting device for the toggle joint in open position has the advantage that pressure which may be exerted from outside against the push button *m* when the switch is closed, does not prevent the toggle joint from operating in case of overload. The arrangement therefore forms an effective and reliable trip-free mechanism and affords a snap action not only when switching off automatically, but also when manually resetting the switch into contact-closing position.

The construction according to the present invention is distinguished from prior art constructions of trip-free switches by its simplicity and small number of parts, due to which it is cheap to manufacture, and also by its small compass, relatively to its current load capacity and by its small weight.

Obvious modifications may be made of the constituent elements of this switch within the scope of the invention. For instance it is not necessary

that the bimetallic strip be directly heated by the current. It may also be indirectly heated. Furthermore, it is immaterial whether the locking element *k* is located in the path of the bimetallic strip or in the path of the other toggle joint element, for instance *i*'. Lastly, it is also immaterial how the element which moves contact *g* into and out of closing position is constructed, i. e. whether it is a two-element toggle joint, such as is shown in the drawing as an example, or any kind of contact moving device including a thermostatically operating bimetallic strip as the source of motion.

I claim:

1. A trip-free circuit breaker for overload protection, comprising a contact arrangement, an overload-responsive bimetallic strip for controlling said contact arrangement, and a pivotally mounted lever yieldingly engaging said strip to form a toggle joint designed to effect a snap movement of said contact arrangement upon the heating by an overload and the cooling of said strip, in combination with a locking element disposed to move into the path of said toggle joint and arranged to be normally held by said joint in inoperative position when the joint is in contact-closing position, means for automatically moving said element into the path of said joint after the latter has moved into contact-opening position to prevent said joint from returning into contact-closing position, and outside means for removing said locking means from said joint path to permit the return of said joint into contact-closing position.

2. A trip-free circuit breaker for overload protection, comprising a snap action contact mechanism, an overload-responsive bimetallic strip designed to vary its moving tendency in dependence upon the occurrence of an overload, said strip forming an actuating part of said contact mechanism, a locking element disposed to be moved into the path of said mechanism and arranged to be held by said mechanism in inoperative position when said mechanism is in contact-closing position, spring means for automatically moving said element into locking position after said mechanism has moved into contact-opening position to prevent the latter from returning into closing position, and outside means for unlocking said locking means to permit said strip to return said mechanism into contact-closing position.

3. A trip-free circuit breaker for overload protection, comprising two contacts, a bimetallic strip for actuating one of said contacts, and a pivotally-mounted lever yieldingly engaging said strip endwise to form a toggle joint designed to effect a contact opening and closing snap movement of said latter contact by the heating and cooling respectively of said bimetallic strip due to overload conditions, in combination with an axially slidable locking pin disposed adjacent and transversely to said strip intermediate its ends, said pin having a cam resting laterally against the edge of said strip when the latter is in contact-closing position, a spring tending to hold said cam against said strip so as to cause said cam to automatically move transversely into the operating path of said strip when the latter has moved into contact-opening position to prevent its return into contact-closing position, and manual resetting means for removing said cam from said strip path to permit the return of said strip into contact-closing position.

HEINRICH SCHACHTNER.
